UNITED STATES PATENT OFFICE.

JOSEPH M. POWELL, OF BROOKLYN, INDIANA, ASSIGNOR TO EAGLE IRON WORKS, OF DES MOINES, IOWA, A CORPORATION OF IOWA.

SHALE PLANER.

Application filed June 22, 1921. Serial No. 479,483.

To all whom it may concern:

Be it known that I, JOSEPH M. POWELL, a citizen of the United States, residing at Brooklyn, in the county of Morgan and 5 State of Indiana, have invented a new and useful Shale Planer, of which the following is a specification.

It is the object of my invention to produce a shale planer which will cut in the arc of 10 a circle and may be fed forward along the center radius of such arc; and to provide a simple and effective arrangement for feeding the machine forward, preferably along the same railroad track on which the hopper-cars run which carry away the shale 15 from the planer; and for swinging the planer in its cutting arc; and for discharging the cut shale into a fixed hopper for all 20 positions which the machine takes in its swinging movement, which hopper in turn may discharge when desired into the hopper-cars.

The accompanying drawings illustrate my invention: Fig. 1 is a side elevation of a shale 25 planer embodying my invention, with the shale bank and parts of the planer itself in section; Fig. 2 is an enlarged section through the rear end of the swinging frame and the pivot car; Fig. 3 is a section on the line 30 3—3 of Fig. 1; Fig. 4 is a plan, on a somewhat smaller scale, of the mechanism shown in Fig. 2; and Figs. 5 and 6 are sections on the lines 5—5 and 6—6 respectively of Fig. 3.

The main frame 10 is shown as of a general triangular form. At its rear apex the frame 10 has a pivotal mounting on a vertical pivotal axis on a pivot car 11 the wheels 12 of which run on a railroad track 13 adjacent the face of the shale bank. The forward end of the frame is supported on an arc-shaped rail 14, upon which rest rollers mounted beneath and supporting the frame 10 and paralleling the two legs of such triangular frame. Conveniently a single roller 15 is provided beneath one of the legs of the frame 10, being mounted in suitable bearing brackets 16 attached to and projecting downward from the frame; this roller 15 is a mere supporting roller. Beneath the other leg of the frame 10 is a driving roller 17, supported in bearing brackets 18 fastened to and extending downward from the frame 10, and this driving roller 17 preferably does 50 not directly engage the rail 14 but instead

rests upon and between two rollers 19 which in turn rest on the rail 14 and are held from separating by links 20 at their ends. This double-roller engagement with the rail 14 increases the traction, to make more efficient 55 the driving of the front end of the frame 10 along the curved rail 14 when the roller 17 is rotated and in turn drives frictionally the rollers 19.

Mounted on the frame 10 is a superstructure 25, which includes an upwardly projecting chain-guide 26 at the forward end of the frame 10, which chain-guide 26 is as high as the top of the shale bank 27 from which shale is to be cut, and is provided 60 with suitable sprockets 28 and 29 at the top and bottom for the cutter chain 30 to travel over. The chain-guide 26 is suitably guyed by guy wires 31 from the rear of the superstructure 25, and preferably inclines forward at its upper end so that the cut on the shale bank 27 will not be quite vertical. The details of the cutter chain form no part of the present invention, but such cutter-chain 65 usually comprises two parallel chain members 30^a and 30^b, cross-connected by bars 32 which carry the cutters 33; and preferably these cutter-carrying bars 32 are prevented from tilting under the reaction of the cutting by tension chains 34 connected to other 70 cross-bars 35 in the manner set forth in my co-pending application Serial Number 479, 80 482, of even filing date herewith.

The cutter chain 30 passes over a driving sprocket 36 in addition to the two sprockets 75 28 and 29. This driving sprocket is mounted on the superstructure 25 near the rear end thereof, on a shaft 37, which shaft is suitably driven from a main driving motor 80 38, mounted on the frame 10, to cause the 85 cutter chain to travel in the direction of the arrow so that the cutters 33 travel downward along the face of the shale bank 27. The driving connection from the motor 38 to the shaft 37 may take any convenient 90 form, and as shown is a speed-reducing drive comprising a belt 39 connecting suitable pulleys on the shaft of the motor 38 and on a shaft 40, and intermeshing gears 41 on the shafts 40 and 37. 95

The cutter chain 30 between the sprockets 29 and 36 travels in a U-shaped trough 45, so that the shale which is cut by the cutters 33 and falls to the bottom of the shale bank 100 is picked up by the cross-bars 32 and 35, 105 110

which are also scrapers, and carried up such trough, as is clear from Fig. 1. The trough 45 extends beyond the sprocket 36, and above such sprocket has a conveyor belt 46 which carries the cut shale on upward to the top of such trough after the pushing action of the cross-bars 32 and 35 on the shale has ceased at the sprockets 36. The upper part of the trough 45 may be slightly depressed with relation to the lower part thereof at the junction point, to allow clearance between the cutter chain and the conveyor belt. The conveyor belt is driven in any suitable manner, the drive as shown being by a chain 47 between sprockets on the shaft 40 and on the shaft 48 which carries the lower end of such conveyor belt.

The upper end of the trough 45 discharges into a hopper 50, which is supported on the upper end of a post 51 carried by the pivot car 11 just behind the pivotal axis on which the frame 10 is mounted on such car. The rear end of the trough 45 projects barely beyond this pivotal axis, so that it will discharge into the hopper 50 for all positions which the frame 10 takes as it swings, and will distribute the shale over such hopper. The hopper 50 is stationary, and at its lower end is provided with the usual hand-controlled gate 52 which when opened permits the hopper 50 to discharge into a hopper-car 53 mounted on the same track 13 which supports the pivot car 11. For mutual steady-
ing, the rear end of the superstructure 25 is connected to the hopper 50 by a V-brace 54, which is pivotally connected to the hopper 50 on the same vertical axis on which the frame 10 is connected to the pivot car 11.

The driving roller 17 has a reversible drive from any convenient source. Conveniently this is from the shaft 55 of the sprocket 29, which shaft is connected through a chain 56 and suitable sprockets to a shaft 57 on which is splined a sleeve 58 carrying two oppositely facing bevel gears 59 either of which by the shifting of the sleeve 58 by a shift lever 60 may be moved into mesh with a bevel gear 61 on a shaft 62 which is connected by suitable bevel gearing 63 to the shaft of the driving roller 17. Thus the driving roller 17 is driven from the motor 38, in one direction or the other according to the position of the shift lever 60.

55 The machine is fed forward into the shale bank by feeding the pivot car 11 forward. For thus feeding the pivot car 11, such car is connected by a forwardly extending pull-screw 65 to an internally threaded cross-piece 66 which may be clamped to the rails of the track 13 in advance of the pivot car 11. By 60 rotating the pull-screw 65, the pivot car 11 is pulled forward. To rotate this pull-screw, such screw is connected by bevel gear- 65 ing 67 to a vertical shaft 68 the axis of which coincides with the pivotal axis between the

frame 10 and pivot car 11, and the upper end of this shaft 68 is connected by bevel gearing 69 to a shaft 70 suitably supported in the frame 10 and provided at its forward end with a bevel gear 71 which may be made to mesh with either of two oppositely facing bevel gears 72 carried by a sleeve 73 splined on a shaft 74 and movable longitudinally thereof by a shift rod 75. The shaft 74 is connected by a chain 76 and suitable sprockets to the shaft 40. Thus the motor 38 furnishes the power for rotating the pull-screw 65, and can rotate such screw in either direction according to the position of the shift rod 75. 75 80

To take the thrust between the pivot car 11 and the frame 10, the pivotal connection between the two is preferably provided by a casting fastened rigidly to the rear end of the frame 10 and both resting on the upper face of the pivot car 11 and having a downward cylindrical extension 78 which fits in a pivot hole in the pivot car 11 and through which the shaft 68 extends. In this way, the shaft 68 is relieved from any stress due to the thrust between the frame 10 and the pivot car 11. 85 90

In operation, the track 13 is laid somewhat in advance of the pivot car 11, the cross-piece 66 is clamped to such track in advance of the pivot car, and, with the cutter chain 30 in proper relation to the shale bank 27, the driving motor 38 is started into operation. This drives the cutter chain 30, to cut shale from the shale bank 27, which shale drops to the bottom of the bank and is carried by the cross-bars 32 and 35 and the conveyor belt 46 up the trough 45 and discharged into the hopper 50. The shift lever 60 is set to cause the frame 10 to swing around the axis of the shaft 68, by the driving action of the rollers 17 and 19. When the frame reaches the end of its swing in one direction, the shift lever is reversed in position to cause it to swing in the other direction, so that the frame swings back and forth in front of the shale bank, and the line of the cutters 33 is constantly being shifted along such bank. From time to time, usually at each end of the swing, the pivot car is fed forward a short distance, usually about an inch, by momentarily shifting the shift rod 75 into the proper position to cause the pull-screw 65 to be turned in the cross-piece 66 to move the pivot car forward the desired distance. This forward movement of the pivot car is preferably made when the frame 10 is at the end of its swing, as because of the length of the swing it may then be done without producing any material movement at that time of the cutters 33 into the shale bank, and the cutters will enter the shale bank as the frame 10 swings toward the other end of its swing. The rollers

15 and 19 are of considerable length, so that there may be a considerable forward movement of the frame 10 without requiring a shifting of the rail 14; and without 5 requiring such rail to be exactly curved to correspond to the arc of movement. When by the forward shifting of the machine the rear ends of the rollers 15 and 19 come into cooperation with the rail 14, such 10 rail is shifted forward by crowbars, each end being thus shifted when the frame 10 is at the other end of such rail. From time to time, as necessity requires, the cross-piece 66 is unclamped from the rails of the track 15 13, and the shift rod 75 is shifted to operate the screw 65 in the reverse direction, thus forcing such cross-piece 66 forward (while the pivot car 11 remains still by reason of the weight upon it) until it is 20 again at the forward end of the pull-screw 65, whereupon it is again clamped to the rails. As the hopper 50 is filled with the shale cut from the bank 27, such shale is discharged therefrom as desired into hopper 25 cars 53, which when filled are pulled away from the machine along the track 13 to allow other cars to be substituted for them beneath the hopper 50.

I claim as my invention:

- 30 1. A shale planer, comprising a pivot car, a track on which said pivot car is mounted, means for feeding said pivot car forward along said track, a frame pivotally mounted on said pivot car, means in addition to said pivot car for supporting said frame and permitting it to swing about its pivotal mounting on the pivot car, and a perpendicularly extending shale-cutting mechanism carried by said frame.
- 35 2. A shale planer, comprising a pivot car, means for feeding said pivot car forward, a frame pivotally mounted on said pivot car, means in addition to said pivot car for supporting said frame and permitting it to swing about its pivotal mounting on the pivot car, and a perpendicularly extending shale-cutting mechanism carried by said frame.
- 40 3. A shale planer, comprising a pivot car, a track on which said pivot car is mounted, a screw projecting forward from said pivot car for pulling the latter forward along said track, means fixed to the track in advance of said pivot car for cooperating with said screw, a frame pivotally mounted on said pivot car, means in addition to said pivot car for supporting said frame and permitting it to swing about its pivotal mounting on the pivot car, and a shale-cutting mechanism carried by said frame.
- 45 4. A shale planer, comprising a pivot car, a screw projecting forward from said pivot car for pulling the latter forward, means fixed in advance of said pivot car for discharging the cut shale into said hopper.
- 50 5. A shale planer, comprising a pivot car, a frame pivotally mounted on said pivot car, means in addition to said pivot car for supporting said frame and permitting it to swing about its pivotal mounting on the pivot car, a perpendicularly extending shale-cutting mechanism carried by said frame, a hopper supported by said pivot car and fixed relatively thereto, and means carried by said frame for discharging the cut shale into said hopper.
- 55 6. A shale planer, comprising a pivot car, a track on which said pivot car is mounted, means for feeding said pivot car forward, a frame pivotally mounted on said pivot car, means in addition to said pivot car for supporting said frame and permitting it to swing about its pivotal mounting on the pivot car, shale-cutting mechanism carried by said frame, power means mounted on said frame for operating said shale-cutting mechanism, and a controllable driving connection from said power means to said screw.
- 60 7. A shale planer, comprising a pivot car, a screw projecting forward from said pivot car for pulling the latter forward, means fixed in advance of said pivot car for cooperating with said screw, a frame pivotally mounted on said pivot car, means in addition to said pivot car for supporting said frame and permitting it to swing about its pivotal mounting on the pivot car, shale-cutting mechanism carried by said frame, power means mounted on said frame for operating said shale-cutting mechanism, and a controllable driving connection from said power means to said screw, said driving connection including a shaft on the pivotal axis on which said frame is mounted on said pivot car.
- 65 8. A shale planer, comprising a pivot car, a track on which said pivot car is mounted, means for feeding said pivot car forward, a frame pivotally mounted on said pivot car, means in addition to said pivot car for supporting said frame and permitting it to swing about its pivotal mounting on the pivot car, a perpendicularly extending shale-cutting mechanism carried by said frame, a hopper supported by said pivot car and fixed relatively thereto, and means carried by said frame for discharging the cut shale into said hopper.
- 70 9. A shale planer, comprising a pivot car, a track on which said pivot car is mounted, means for feeding said pivot car forward, a frame pivotally mounted on said pivot car, means in addition to said pivot car for supporting said frame and permitting it to swing about its pivotal mounting on the pivot car, shale-cutting mechanism carried by said frame.
- 75 10. A shale planer, comprising a pivot car, means for feeding said pivot car forward, a frame pivotally mounted on said pivot car, means in addition to said pivot car for supporting said frame and permitting it to swing about its pivotal mounting on the pivot car, shale-cutting mechanism carried by said frame, power means carried by said frame for operating said shale-cutting mechanism, and means for driving said pivot-car-feeding means from said power means.
- 80 11. A shale planer, comprising a pivot car, a screw projecting forward from said pivot car for pulling the latter forward, means fixed in advance of said pivot car for cooperating with said screw, a frame pivotally mounted on said pivot car, means in addition to said pivot car for supporting said frame and permitting it to swing about its pivotal mounting on the pivot car, shale-cutting mechanism carried by said frame, power means mounted on said frame for operating said shale-cutting mechanism, and a controllable driving connection from said power means to said screw.
- 85 12. A shale planer, comprising a pivot car, a screw projecting forward from said pivot car for pulling the latter forward, means fixed in advance of said pivot car for cooperating with said screw, a frame pivotally mounted on said pivot car, means in addition to said pivot car for supporting said frame and permitting it to swing about its pivotal mounting on the pivot car, shale-cutting mechanism carried by said frame, power means mounted on said frame for operating said shale-cutting mechanism, and a controllable driving connection from said power means to said screw.
- 90 13. A shale planer, comprising a pivot car, a screw projecting forward from said pivot car for pulling the latter forward, means fixed in advance of said pivot car for cooperating with said screw, a frame pivotally mounted on said pivot car, means in addition to said pivot car for supporting said frame and permitting it to swing about its pivotal mounting on the pivot car, shale-cutting mechanism carried by said frame, power means mounted on said frame for operating said shale-cutting mechanism, and a controllable driving connection from said power means to said screw.
- 95 14. A shale planer, comprising a pivot car, a screw projecting forward from said pivot car for pulling the latter forward, means fixed in advance of said pivot car for cooperating with said screw, a frame pivotally mounted on said pivot car, means in addition to said pivot car for supporting said frame and permitting it to swing about its pivotal mounting on the pivot car, shale-cutting mechanism carried by said frame, power means mounted on said frame for operating said shale-cutting mechanism, and a controllable driving connection from said power means to said screw.
- 100 15. A shale planer, comprising a pivot car, a screw projecting forward from said pivot car for pulling the latter forward, means fixed in advance of said pivot car for cooperating with said screw, a frame pivotally mounted on said pivot car, means in addition to said pivot car for supporting said frame and permitting it to swing about its pivotal mounting on the pivot car, shale-cutting mechanism carried by said frame, power means mounted on said frame for operating said shale-cutting mechanism, and a controllable driving connection from said power means to said screw.
- 105 16. A shale planer, comprising a pivot car, a screw projecting forward from said pivot car for pulling the latter forward, means fixed in advance of said pivot car for cooperating with said screw, a frame pivotally mounted on said pivot car, means in addition to said pivot car for supporting said frame and permitting it to swing about its pivotal mounting on the pivot car, shale-cutting mechanism carried by said frame, power means mounted on said frame for operating said shale-cutting mechanism, and a controllable driving connection from said power means to said screw.
- 110 17. A shale planer, comprising a pivot car, a screw projecting forward from said pivot car for pulling the latter forward, means fixed in advance of said pivot car for cooperating with said screw, a frame pivotally mounted on said pivot car, means in addition to said pivot car for supporting said frame and permitting it to swing about its pivotal mounting on the pivot car, shale-cutting mechanism carried by said frame, power means mounted on said frame for operating said shale-cutting mechanism, and a controllable driving connection from said power means to said screw.
- 115 18. A shale planer, comprising a pivot car, a screw projecting forward from said pivot car for pulling the latter forward, means fixed in advance of said pivot car for cooperating with said screw, a frame pivotally mounted on said pivot car, means in addition to said pivot car for supporting said frame and permitting it to swing about its pivotal mounting on the pivot car, shale-cutting mechanism carried by said frame, power means mounted on said frame for operating said shale-cutting mechanism, and a controllable driving connection from said power means to said screw.
- 120 19. A shale planer, comprising a pivot car, a track on which said pivot car is mounted, means for feeding said pivot car forward, a frame pivotally mounted on said pivot car, means in addition to said pivot car for supporting said frame and permitting it to swing about its pivotal mounting on the pivot car, shale-cutting mechanism carried by said frame, power means mounted on said frame for operating said shale-cutting mechanism, and a controllable driving connection from said power means to said screw.
- 125 20. A shale planer, comprising a pivot car, a track on which said pivot car is mounted, means for feeding said pivot car forward, a frame pivotally mounted on said pivot car, means in addition to said pivot car for supporting said frame and permitting it to swing about its pivotal mounting on the pivot car, shale-cutting mechanism carried by said frame, power means mounted on said frame for operating said shale-cutting mechanism, and a controllable driving connection from said power means to said screw.
- 130 21. A shale planer, comprising a pivot car, a track on which said pivot car is mounted, means for feeding said pivot car forward, a frame pivotally mounted on said pivot car, means in addition to said pivot car for supporting said frame and permitting it to swing about its pivotal mounting on the pivot car, shale-cutting mechanism carried by said frame, power means mounted on said frame for operating said shale-cutting mechanism, and a controllable driving connection from said power means to said screw.

4

along said track, a frame pivotally mounted on said pivot car, means in addition to said pivot car for supporting said frame and permitting it to swing about its pivotal mounting on the pivot car, a perpendicularly extending shale-cutting mechanism carried by said frame, a hopper supported by said pivot car and fixed relatively thereto in position to discharge into a car movable on the same track on which the pivot car is mounted, and means carried by said frame for discharging the cut shale into said hopper.

10. A shale planer, comprising a pivot car, means for feeding said pivot car forward, a frame pivotally mounted on said pivot car, means in addition to said pivot car for supporting said frame and permitting it to swing about its pivotal mounting on the pivot car, shale-cutting mechanism carried by said frame, a hopper supported by said pivot car and fixed relatively thereto, means carried by said frame for discharging the cut shale into said hopper, and 25 a brace between said hopper and said frame, said brace having a pivot in the axis on which said frame is connected to said pivot car.

11. A shale planer, comprising a pivot car, a track on which said pivot car is mounted, means for feeding said pivot car forward along said track, a frame pivotally mounted on said pivot car, shale-cutting mechanism carried by said frame, means for

supporting the forward end of said frame at two laterally separated points, said supporting means at one of said points comprising a roller, a curved rail on which said roller travels, and means for reversibly driving said roller.

12. A shale planer, comprising a pivot car, means for feeding said pivot car forward, a frame pivotally mounted on said pivot car, shale-cutting mechanism carried by said frame, means for supporting the forward end of said frame at two laterally separated points, said supporting means at one of said points comprising a roller, a curved rail on which said roller travels, and means for reversibly driving said roller.

13. A shale planer, comprising a pivot car, means for feeding said pivot car forward, a frame pivotally mounted on said pivot car, shale-cutting mechanism carried by said frame, means for supporting the forward end of said frame at two laterally separated points, said supporting means at one of said points including a driving roller, two rollers upon and between which said driving roller rests, and a curved track upon which said last two rollers rest so that they may roll thereon, and means for reversibly operating said driving roller.

In witness whereof, I have hereunto set my hand at Indianapolis, Indiana, this 1st day of June, A. D. one thousand nine hundred and twenty-one.

JOSEPH M. POWELL.
